COMBINED SIGNAL LAMP AND TRUCK BED
RUB RAIL CORNEREdward S. Grumbache, Paris, Ill., assignor to
Electrographic Corporation, New York, N. Y., a
corporation of Delaware

Application November 12, 1947, Serial No. 142,499

Term of patent 14 years

(Cl. D14—6)

To all whom it may concern:

Be it known that I, Edward S. Grumbache, a citizen of the United States of America, and resident of Paris, county of Edgar, and State of Illinois, have invented a new, original, and ornamental Design for a Combined Signal Lamp and Truck Bed Rub Rail Corner, of which the following is a specification, reference being had to the accompanying drawings, forming part thereof.

Fig. 1 is a perspective view of a combined signal lamp and truck bed rub rail corner embodying my new design, as viewed from centrally and above said corner;

Fig. 2 is a top plan view of the combined signal lamp and rub rail corner shown in Fig. 1;

Fig. 3 is a side elevational view of the combined signal lamp and rub rail corner shown in Fig. 1;

Fig. 4 is an elevational view of the combined signal lamp and rub rail corner shown in Fig. 1 as viewed in the direction of the arrow marked 4 in Fig. 2; and,

Fig. 5 is an elevational view of the combined signal lamp and rub rail corner shown in Fig. 1 as viewed in the direction of the arrow marked 5 in Fig. 2.

The dotted line showing in the several drawing figures is for illustrative purposes only.

I claim:

The ornamental design for a combined signal lamp and truck bed rub rail corner, as shown and described.

EDWARD S. GRUMBACHE.
